AMPLIFICATION AND REPRODUCTION OF ELECTRICAL IMPULSES.

Application filed November 4, 1924. Serial No. 747,800.

My invention relates to electrical systems of the signalling type and especially to an improved amplifying relay system employing the so-called "push-pull" principle of amplification. My invention also relates to amplification and signalling methods.

Amplifying relay systems heretofore employed possess the disadvantage of sluggish operation owing to transient conditions inherent in the systems themselves and in the systems with which they are associated with a resulting distortion of the signals especially at comparatively high keying frequencies.

One of the principal objects of my invention is the provision of an amplifying relay system in which the above disadvantage is obviated.

Another principal object of my invention is the provision of an improved amplifying relay system possessing the following advantages:

(1) The establishment of a substantially in phase relationship between the signal impulses and the corresponding amplified current impulses over a considerable range of keying frequencies for a given setting of the adjustable elements.

(2) Faithful reproduction of the signal impulses greatly amplified with the substantial elimination of distortion over a considerable range of keying frequencies.

(3) Faithful reproduction, if desired, of substantially all impulses including both signal impulses and interfering impulses.

(4) The elimination of the effects of certain kinds of static on the amplified signal impulses.

(5) Speed in the reception of signal impulses.

(6) The realization of very quick relay action by the production of amplified impulses having strong initial amplitudes followed by a tapering off of said initial amplitudes with the quick termination of the amplitudes at the proper time.

(7) The production of purified amplified impulses to produce positive action from weak and uncertain signal impulses.

Other objects and advantages of my invention will be apparent from the following description taken in connection with the accompanying drawing in which:

Fig. 1 is a schematic diagram of a preferred embodiment of my improved push-pull amplifying relay system.

Figs. 2, 3, 4, 5, and 6 are diagrammatic illustrations of the manner in which my system functions.

Referring to Fig. 1 two signal input leads 1 and 2 connect the out-put terminals of the source of received signal impulses to the outer extremities of resistances R_1 and R_2 , respectively which are connected together at their inner extremities by lead 3.

My improved amplifying system comprises two triodes T_1 and T_2 .

The plate filament circuit of triode T_1 comprises the following elements connected in the following manner: a lead 4 connects the upper extremity of resistance R_1 to one extremity of resistance R_3 , the other extremity of resistance R_3 being connected to the minus terminal of the plate battery B_1 . The plus terminal of plate battery B_1 is connected to one extremity of relay coil 6 by lead 7. The other extremity of coil 6 is connected to the plate element of triode T_1 through a resistance R_5 , having a variable condenser C_1 connected in shunt therewith as shown. The filament of triode T_1 is connected to the junction point of resistances R_1 and R_2 by lead 8 as shown.

The plate filament circuit of triode T_2 comprises the following elements connected in the following manner: a lead 9 connects the lower extremity of resistance R_2 to one extremity of resistance R_4 , the other extremity of resistance R_4 being connected to the minus terminal of plate battery B_2 . The plus terminal of plate battery B_2 is connected to one extremity of relay coil 10 by lead 11. The other extremity of coil 10 is connected to the plate element of triode T_2 through a resistance R_6 having a variable condenser C_2 in shunt therewith as shown. The filament of triode T_2 is connected to the junction point of resistances R_1 and R_2 by the lead 8 as shown.

The filament currents for the two triodes may be supplied from the common source A , independent control of the individual filament currents being accomplished by means of the variable rheostats r_1 as shown.

The condensers C_1 and C_2 are preferably simultaneously controlled by a single control means as shown. However, I do not limit myself to such a control means as it is obvious that the condensers may be controlled independently of each other if desired.

The grid element of triode T_1 is connected to the plus terminal of the biasing battery C^1 , the minus terminal of said battery being con-

nected to the junction point of resistance R_4 and the minus terminal of plate battery B_2 as shown.

The grid element of triode T_2 is connected 5 to the minus terminal of the biasing battery C^2 , the plus terminal of said biasing battery being connected to the junction point of resistance R_3 and the minus terminal of plate battery B_1 .

10 The resistance R_1 is preferably made equal to the resistance R_2 , the resistance R_3 to R_4 and the resistance R_5 to R_6 . However, I do not limit myself to such an apportionment of resistance values, but may appropriately vary 15 the relationship between the values of said resistances depending on the characteristics desired.

The biasing battery C^1 is arranged to give the grid of triode T_1 a more positive bias 20 than C^2 gives to the grid of triode T_2 .

The relay 5 comprises coils 6 and 10 for rocking the pivoted armature 12 to cause a movable contact 13 to alternately contact with the stationary contacts 14 and 15 which may be 25 employed for marking and spacing contacts. The contacts of the relay 5 may control any impulse or signal responsive device such as a telegraph sounder, telephone receiver, printing mechanism, retransmitting system, etc.

30 The above described system functions in the following manner: Assume that no signal impulses are being received. Owing to the fact that the grid element of triode T_1 has more of a positive bias than that of triode T_2 , 35 because of the extra bias imparted to it by the battery C^1 , more current will flow in its plate-filament circuit. This current will cause a slight energizing of relay coil 6 and a voltage drop through the resistances R_1 and R_3 . 40 Due to this voltage drop the grid element of triode T_2 will have a negative bias imparted to it and consequently a condition is quickly set up of no current flowing in the plate-filament circuit of triode T_2 and full plate current 45 rent in triode T_1 .

The inductances of the relay coils 6 and 10 and the capacities of the condensers C_1 and C_2 substantially determine the time constants of the plate-filament circuits of triodes T_1 and T_2 respectively. The time constants of the plate-filament circuits of triodes T_1 and T_2 are appropriately adjusted to the frequency of the signal impulses impressed on the system by suitable adjustment of the condensers C_1 and C_2 . However, the triodes T_1 and T_2 are prevented from functioning as oscillation generators by a suitable value of the biasing batteries C^1 and C^2 .

Referring to Fig. 2, assume a signal pulse 60 representing say a "dash" is impressed on the resistances R_1 and R_2 . The current due to this pulse, which attains its average amplitude very suddenly and maintains the same for some length of time, causes a sudden

voltage drop through the resistances R_1 and R_2 . This voltage drop makes the grid element of T_2 less negative than it was before and the grid element of T_1 negative rather than positive as it was before. The current at once starts to flow in the plate-filament circuit of triode T_2 graphically represented by curve b while the simultaneous diminution of current takes place in the plate-filament circuit of triode T_1 graphically represented by curve a .

The plate-filament circuit current of triode T_2 then effects a voltage drop through the resistances R_2 and R_4 , which further decreases the plate-filament circuit current of triode T_1 and further increases the plate-filament circuit current of triode T_2 . This action of course, takes place rapidly owing to the fact that practically only resistances are present in the system which comprises substantially no inductive reactance.

The decrease of the plate-filament current of triode T_1 and the increase of the plate-filament circuit current of T_2 is accentuated by the condensers C_1 and C_2 respectively. A few instants later the plate-filament circuit current of triode T_2 tapers off to a lower steady value as shown by curve b at d owing to the disappearance of the transient conditions created by the extra charge on condenser C_2 which permitted the initial extra flow of current at the start and the limiting action of the resistance R_6 in maintaining a substantially lower but steady current for the remainder of the pulse.

The sudden decay of current in the plate-filament circuit of triode T_1 results in the sudden de-energization of relay coil 6; whereas the sudden increase of the plate-filament circuit current of triode T_2 to its maximum amplitude causes a sudden energization of relay coil 10 resulting in the vigorous movement of the armature 12 to effect contact between contacts 13 and 15. The tapering off of the current in the plate-filament circuit of triode T_2 a few instants later results in the reduced energization of coil 10 which is very desirable owing to the fact that the holding power required of coil 10 is not as great as the power required to effect the quick movement of the armature 12.

As soon as the signal pulse disappears, the voltage drops in the resistances R_1 and R_2 disappear; the grid element of triode T_2 again becomes negative while the grid element of triode T_1 again becomes positive. The current in the plate-filament circuit of triode T_2 suddenly decays to zero as shown by curve b while the current in the plate-filament circuit of T_1 suddenly builds up to its maximum amplitude as shown by curve c owing to the action of the condensers C_2 and C_1 respectively.

The coil 10 of relay 5 is thus suddenly de-

energized while the coil 6 is suddenly energized to its maximum value resulting in the vigorous movement of armature 12 to effect contact between the contacts 13 and 14.

- 5 The current in the plate-filament circuit of T_1 a few instants later tapers off to a lower value as shown by curve *c* owing to the disappearance of the transient conditions created by the condenser C and the influence of 10 the resistance R_5 . A decreased energization of coil 6 therefore results as shown by curve *c*.

It is thus seen that the sudden maximum energization of one coil of the relay is effected while the other coil is simultaneously quickly 15 de-energized, this maximum energization tapering off to a lower holding value a few instants later resulting in quick and positive relay action. The system is now ready for the reception of another signal impulse.

- 20 Curves *a'*, *b'* and *c'* of Fig. 3 corresponding to curves *a*, *b* and *c* respectively of Fig. 2, graphically represent the functioning of the same system upon the reception of a "dot" impulse instead of a "dash" impulse.

25 It is obvious that the shapes of the transient portions of the curves shown in Figs. 2 and 3 may be modified within rather wide limits to obtain the desired advantages for different signalling conditions.

- 30 For example the faithful amplification and reproduction of all the impulses including both signal impulses and interfering impulses may be desired. In this case a very perfect relay action will be necessary in order that the 35 amplifying system may closely follow all of the actual impulses impressed on it such as for example the impulses due to static as well as the signal impulses. To accomplish this result the condensers C_1 and C_2 should have

40 small capacity values in order that the transient current surges may be of very short duration. In fact for absolutely faithful amplification and reproduction the condensers C_1 and C_2 may be eliminated entirely in order 45 that the amplifying system may have a very high time constant resulting in the substantially instantaneous response to all impulses impressed thereon.

It has long been thought that reliance could 50 not be placed on mechanical relay action for the faithful reproduction and amplification of received impulses. It has also been thought that errors would be introduced in the reception of radio telegraphic signals by 55 the use of relays due to the fact that static pulses would be lengthened out and merged into each other to make false dots and dashes resulting in the reception of faulty signals. However, the above mentioned conclusions 60 are based on the action of relays employed in the usual telegraphic systems where the action is relatively very sluggish as compared with the short pulses characteristic of static encountered in radio signalling systems.

- 65 The relay 5 is preferably of the usual

sensitive type employed in ordinary telegraphy. However, the employment of my improved push pull amplifying system in connection with a mechanical relay raises the time constant of the entire amplifying system 70 to such a degree that the mechanical relay 5 will respond readily and effectively to these short static pulses. Figs. 4 and 5 show the records obtained by two sensitive siphon recorders of the pulses in the input and output, respectively, of the amplifying relay system. The ordinates of Figs. 4 and 5 represent energy amplitudes while the abscissæ represent time. It is readily seen from a perusal of Figs. 4 and 5 that all but the smallest pulses are recorded in the output of the amplifying system.

The mechanical relay 5 closes at each pulse and gives a true picture of the value of each pulse by reason of the fact that the marking contacts remain closed for such a short period of time that the recording arm of the siphon recorder does not have sufficient time to rise to its full value. In other words a condition has been established where the mechanical 90 relay actually has a higher time constant and its movable contacts move with higher speed than the high speed siphon recorders usually employed in work of this nature.

Assuming a dot impulse occurs in a given 95 unit of time, a dash impulse in three of said units of time, a spacing between impulses constituting the same character in one of said units of time, a spacing period between letters in three of said units of time, and a spacing period between words in five of said units of time; a keying cycle may then be said to occur within two of the said units of time.

It has been ascertained by experiment that the average five letter word comprises twenty-four of the above mentioned cycles. Therefore, if sixty words are being transmitted per minute, the keying frequency may be said to be twenty-four cycles; and, if one hundred words are being transmitted per minute, the 110 keying frequency may be said to be forty cycles. Every transmitting rate may therefore be said to have its corresponding keying frequency.

The use of mechanical transmitters for keying signals in a wired telegraph system or to the radio transmitting device has become very common practice where high speed transmission is desired. When such transmitters are employed, the dots, dashes and spacing periods are formed with great accuracy and it is important that the receiving apparatus faithfully reproduce these dots, dashes and spacing periods. It is also important that the received signals be clearly differentiated from 120 interference or static.

In order to realize faithful reproduction and amplification of the received signal impulses, the time constant of my improved push-pull amplifying system is chosen to be 130

substantially equal to the reciprocal of the keying frequency employed at the transmitting station. For example, if the signals are being transmitted at a rate of one hundred words per minute, the condensers C_1 and C_2 with their related resistances R_5 and R_6 will be so adjusted that the transient pulses in the output of the system will correspond very closely to the keying cycle of the transmitted signal.

Referring to Fig. 6, curve e shows the received pulses impressed on the grid filament circuits of the triodes T_1 and T_2 . Curve f shows the amplified pulses in the output circuits of the triodes corresponding to the pulses of curve e . The above described amplifying system is arranged to oscillate very slightly at a frequency substantially equal to the keying frequency employed at the transmitting station. The biasing batteries C^1 and C^2 will prevent the triodes T_1 and T_2 from oscillating in any other manner. This imparts a gently swinging characteristic to the output circuits of the triodes T_1 and T_2 as seen in curve f , which with continued signalling, is adjusted to be substantially in phase with the keying frequency. These gentle swings are in themselves insufficient to actuate the relay armature 13; but they will substantially aid in the faithful reproduction of the desired signal impulses and will oppose out of phase disturbances as shown.

When the amplitude of an amplified received signal pulse attains a value located with in the zone g of curve f , the relay armature definitely makes a marking or spacing contact and holds the same until the amplitude again attains a value within the zone g of a succeeding portion of the signal pulse. This results in very much improved and clear-cut signal pulses from the relay 5 as shown by the curve h of Fig. 6. It is therefore obvious from the above discussion that the adjustment of the time constant of the amplifying system to the keying frequency results in considerably improved and clear-cut signal pulses with the substantial elimination of the effects of various disturbances on the amplified signal pulses.

My amplifying system is especially useful in the operation of signal printing devices and other signal responsive devices requiring definite marking and spacing pulses with as great a suppression of disturbances as possible for their successful functioning. My improved amplifying system is also especially useful in re-transmission systems where it is necessary to take weak signals and convert them into clear-cut strong signals for re-transmission. While I have cited above a few applications of my improved amplifying system, I wish it distinctly understood that said applications are merely cited by way of examples as there are many other applications which might be made.

The table below gives the ohmic values allotted to the various resistances R_1 , R_2 , R_3 , R_4 , R_5 and R_6 ; the terminal voltage of the various batteries B_1 , B_2 , C^1 and C^2 and the capacity in micro-farads allotted to the condensers C_1 and C_2 for various conditions which might be desired.

Conditions	Ohms						Volts			M. F.		75	
	R_1	R_2	R_3	R_4	R_5	R_6	B_1	B_2	C^1	C^2	C_1	C_2	
1	1000	1000	1500	1500	10000	10000	+90	+90	+3	-3	1	1	80
2	1000	1000	1500	1500	10000	10000	+90	+90	+3	-3	2.5	2.5	
3	1000	1000	1500	1500	10000	10000	+90	+90	+3	-3	4	4	

Condition 1 corresponds to the case where faithful reproduction and amplification of all of the pulses impressed on the amplifying system are desired. Condition 2 corresponds to the case where faithful reproduction and amplification of the signal pulses and the minimizing of the effects of interfering pulses are desired when the signals are transmitted at a keying frequency of 40 cycles (100 words per minute). Condition 3 corresponds to the case where faithful reproduction and amplification of the signal pulses and the minimizing of the effects of disturbing pulses are desired when the signals are transmitted at a frequency of 24 cycles (corresponding to 60 words per minute).

The values in the above table are given merely for the purpose of enabling those skilled in the art to practice the invention and it is to be distinctly understood that I do not limit myself to these values. It is also obvious that the capacities of the condensers C_1 and C_2 and the values of the various resistances and batteries may be so chosen as to effect the faithful reproduction and amplification of the signal pulses transmitted at keying frequencies other than 24 cycles and 40 cycles.

While I have shown and described a preferred embodiment of my invention I do not limit myself to the same but may employ such other embodiments as come within the spirit and scope of my invention.

Having described my invention, what I claim is:

1. The combination with means for receiving signal impulses comprising resonant circuits of means for faithfully reproducing and amplifying said signal impulses comprising a pair of balanced triode amplifiers, and means comprising circuits having adjustable time constants and a double winding relay for producing amplified signal impulses, the amplified signal impulses being substantially in phase with the received signal impulses for a considerable range of keying frequencies.

2. The combination with means for receiving electrical impulses comprising receiving circuits of means for faithfully reproducing

- and amplifying said impulses comprising a pair of resistances connected thereto and producing a voltage drop corresponding to said signal impulses, a pair of balanced amplifier devices connected thereto, a double winding relay having its windings respectively connected to said triodes and time controlled means for maintaining biasing potentials on the grids of said triodes at different values.
10. 3. The combination with means for receiving electrical impulses including both signaling impulses and disturbing impulses of means for faithfully reproducing and amplifying substantially all of said impulses comprising vacuum tube circuits having adjustable time constants cooperating therewith, a mechanical relay actuated thereby, and means for applying differential biases upon the grids of said tubes for holding said relay in a biased position.
4. The combination with means for receiving signal impulses and disturbing impulses bearing certain predetermined relationships to the signal impulses of means for faithfully reproducing and amplifying the signal impulses and substantially eliminating the effects of the disturbing impulses comprising resistance input means, a pair of balanced differentially biased triode amplifier devices connected thereto through a pair of locking resistances adapted supply a supplemental bias to said amplifiers and a mechanical relay operated thereby.
5. In a signal reproducing device, the combination of resistance input means, a pair of differentially biased triode amplifiers, a mechanical relay associated with the output circuit of each of said triodes and resistance means for locking said arrangement whereby signal impulses of a current strength below a predetermined value have no effect on the current passed through said triode amplifiers and produces no action in said relay.
6. The combination with means responsive to weak and uncertain signal impulses of means for producing strong and purified amplified impulses from said signal impulses comprising a pair of balanced triode amplifier devices, a resistance input means therefor, a mechanical relay operated thereby, differential grid bias means connected thereto and means for producing a strong current change to move said relay followed by a weaker holding current.
7. The combination with means responsive to signal impulses comprising a non-oscillating relay of an amplifying system cooperating therewith and having its time constant adjusted to bear a predetermined relationship to the keying frequency of the transmitted signal impulses.
8. The combination with a non-resonant mechanical relay and associated triode amplifier means, of a condenser and charging resistance in parallel therewith connected in the output circuits of said triodes and associated with said relay whereby said relay action upon the triode passing current is considerably accentuated.
9. In a signal repeater, the combination of a pair of balanced amplifier devices, a non-oscillating relay actuated thereby, and time controlled grid bias means for controlling the initial pulse of current supplied to said relay in response to signal changes passing through a critical amplitude zone.
10. The method of receiving signals and excluding static interference which consists in actuating a relay by means of balanced triode amplifier devices having differential grid bias means, whereby said relay is caused to respond quickly to signal impulses above a definite value and to be unresponsive to impulses below a definite value.
11. The method of controlling the operating characteristics of a mechanical relay which comprises including in its input circuit a triode amplified means and connecting therebetween circuits having a controlled time delay constant for accentuating the action of said relay upon the receipt of current pulses in said amplifier.
12. In a signal repeater the combination of a pair of balanced amplifiers, a non-oscillating relay, and time controlled amplifier grid bias means for controlling the current output of said amplifier and actuating said relay only in response to signal changes passing through a critical amplitude zone, said time controlled means including a capacity and parallel connected resistance in the output circuit of each amplifying device, said means being connected between said amplifying devices and said relay.
13. In a signal indicating system, the combination of a differential relay and a pair of vacuum tubes having plate circuits for actuating the relay differentially associated therewith, means for biasing the grids of said tubes to normally close the relay on one of its contacts, means for oppositely modifying the bias of said grids to change the relative values of the currents in the plate circuits of said tubes to close the relay on its other contact, and a condenser with a charging resistance in parallel therewith in the plate circuit of each tube for momentarily accentuating the change in the plate currents.
14. In a signal indicating system the combination of a differential relay and a pair of vacuum tubes having plate circuits for actuating the relay and differentially associated therewith of, means for biasing the grids of said tubes to normally close the relay on one of its contacts, means for oppositely modifying the bias on the grid of the second tube for causing relative change in the plate currents of said tubes, whereby said relay is closed upon its other contact, means for accentuating the first rush of current through said sec-

ond tube for aiding the action of said relay and means connected in the plate circuit of each tube and common to the grid circuit of the other tube for presenting an extra bias 5 on the grid of said tube members whereby disturbing influences in signal reception not reaching a predetermined current value produce no effect on said relay.

15. In a signal indicating system, a source 10 of received signals, a pair of vacuum tubes resistively and differentially connected thereto, means for biasing the grids of said tubes, whereby one tube is passing current on conditions of no signal pulses and the other tube 15 passes current at a time when signal pulses are received, a differential relay connected in the plate circuit of said tubes, and means in the plate circuit of each of said tubes for accentuating the initial pulse of current 20 through said tubes, whereby the speed of relay action upon receipt of incoming signals is considerably aided.

16. In a signal indicating system, the combination of a pair of differentially biased triode amplifiers, a double acting relay connected in the output circuit of said tubes, whereby the relay marks dots or dashes and spaces 25

in accordance with which of said tubes pass current, a separate source of a plate current for each of said differentially biased triodes, and means actuated by the receipt of signals from a source for oppositely modifying the bias on the grids of said tubes, whereby the strength of current flowing through is increased in one of said tubes and decreased 35 through the other of said tubes, and means connected in the plate circuit of each of said tubes for momentarily accentuating the change in plate currents, whereby the relay action is made considerably faster. 40

17. The combination with means for receiving electrical impulses including both signalling impulses and disturbing impulses of means for faithfully reproducing and amplifying substantially all of said impulses comprising vacuum tube circuits having adjustable time constants cooperating therewith, a current responsive device actuated by said vacuum tube circuits, and means for applying differential biasing potentials on the grids of said vacuum tubes for controlling the operation of said current responsive device. 45 50

RICHARD H. RANGER.
